UNITED STATES PATENT OFFICE.

JOSEPH ELMER McGINNESS, OF PITTSBURG, PENNSYLVANIA.

HORIZONTALLY-PIVOTED WINDOW.

SPECIFICATION forming part of Letters Patent No. 760,140, dated May 17, 1904.

Application filed February 23, 1904. Serial No. 194,757. (No model.)

To all whom it may concern:

Be it known that I, JOSEPH ELMER McGINNESS, a citizen of the United States, residing at Pittsburgh, in the county of Allegheny and State of Pennsylvania, have invented a new and useful Improvement in Horizontally-Pivoted Windows, of which the following is a specification.

The invention relates to windows having the sash horizontally pivoted to strips on each side, which strips are adapted to be separated laterally from the sash and to travel longitudinally in the grooves of the window-frame; and the object of the improvement is to provide a simple pivotal connection between the sash and the strip by means of which the sash can be stopped or held in various positions of rotation. This object is attained by the arrangement, construction, and mechanism illustrated in the accompanying drawings, in which—

Figure 1 is a fragmentary side view of a window frame and sash, showing the pivotal connection in longitudinal section; Fig. 2, an enlarged longitudinal section of the pivotal parts in the strip with the sash rotated to show a cross-section of the pivotal parts therein; Fig. 3, a cross-section of the frame and sash on line 3-3, Fig. 1; Fig. 4, a detached perspective view of the swivel; Fig. 5, a detached perspective view of the sash-plate; Fig. 6, a detached perspective view of the strip-plate; Fig. 7, a detached perspective view of the spiral spring; Fig. 8, a detached perspective view of the washer, and Fig. 9 a detached perspective view of the swivel-pin.

Similar numerals refer to similar parts throughout the drawings.

The window-frame 1 is made in the usual manner with a groove 2 on each side for receiving the respective sash-strips. The sash 3 is made less in width than the inside clear width of the frame, and the usual strips, as 4, are pivoted on the side edges of the sash and are adapted to operate in the respective frame-grooves. The adjoining faces 5 and 6 of the sash edge and side strip are provided with grooves 5^a and 6^a and ridges 5^b and 6^b, having inclined sides, so that when the sash and strips are alined and brought together the respective ridges enter and fit into the corresponding

grooves, as shown particularly in Fig. 3, and when the sash is rotated on the strips the ridges are forced out of the grooves and bear against the crests of the opposing ridges, thus separating the strips from the sash according to the depth of the grooves, as shown in Fig. 2.

Each pivotal connection is composed of the sash-plate 7, the strip-plate 8, the swivel 9, the swivel-pin 10, the spring 11, and, preferably, the washer 12 and is best located in the transverse axis of the sash. The sash-plate 7 is countersunk in the side edge of the sash, where it is attached, as by the screws 13. The face of the sash-plate is grooved and ridged like the edge of the sash and on the rear side is provided the swivel-hub 14, in which is found the axial swivel-bearing 14^a. Across the rear end of this hub are provided the series of ribs 15, which have the inclined sides 16 and are preferably radially located, as shown. In front of the swivel-bearing and extending to the face of the sash-plate is provided the somewhat larger and likewise axial main bearing 17 of the pivotal connection.

The strip-plate 8 is countersunk in the sash side of the strip, where it is attached, as by the screws 18. The face of the strip-plate is grooved and ridged like the side strip, and on the same side is preferably provided the pivot-hub 19, in which is provided the axial swivel-aperture 20, and which hub is adapted to enter endwise and rotate in the main bearing of the sash-plate. The rear part of the swivel-aperture is somewhat enlarged to form the socket 21 with the annular shoulder or seat 22 for the spiral spring 11, and on the rear side of the strip-plate are provided the lugs 23 on each side of the spring-socket, between which lugs are formed the diametrically opposite guide-slots 24, in which the ends of the swivel-pin 10 are adapted to operate. The swivel 9 comprises the shank 25, having the transverse hole 26 in one end for the pin 10 and the head 27 on the other end, across the inner face of which head are provided the grooves 28, preferably with inclined sides, which grooves correspond in location and arrangement with the ribs on the rear end of the swivel-hub of the sash-plate.

The parts of the pivotal connection are as-

sembled by bringing the grooved and ridged faces of the sash and strip plates together, with the ridges of the one entered in the grooves of the other and with the pivot-hub 5 of the strip-plate entered in the main bearing of the sash-plate, and the shank of the swivel is then entered through the swivel-bearing of the sash-plate and the axial aperture of the strip-plate to bring the ribs on the sash-plate 10 hub into the grooves on the swivel-head, after which the spiral spring is placed around the swivel-shank against its seat in the strip-plate socket. The washer is placed around the swivel-shank against the spiral spring, and 15 the swivel-pin is entered through the hole in the end of the swivel-shank, with its side against the washer and its ends in the guide-slots between the lugs on the strip-plate, in which normal relation of the parts the spiral 20 spring is so confined or compressed that its energy acts to prevent a separation of the sash-plate from the strip-plate and of the swivel-head from the sash-plate hub.

With the parts of the pivotal connection 25 thus assembled and the respective plates attached to the sash and the strip, one on each side of the window, and with the strips entered in the window-frame grooves the sash is adapted to be rotated on its horizontal pivots 30 by merely pulling or pushing the upper or lower end of the sash. In such rotation the side strips are of course separated from the edges of the sash in the usual manner by the action of the inclined sides of the ridges on 35 the one against the similar inclined sides on the other until the crests of the ridges of the one ride on the crests of the ridges of the other, as shown in Fig. 2, and the endwise movement of the swivel-shank in the axial 40 aperture of the strip-plate necessary to accommodate this separation is permitted by the movement of the swivel-pin in the guide-slots between the lugs on the strip-plate to the position shown by full lines in Fig. 2, and as 45 the swivel is held against rotation by the swivel-pin in the guide-slots the rotation of the sash also acts to separate the swivel-head from the sash-plate hub, which is accomplished by the action of the inclined sides of the hub- 50 ribs against the inclined sides of the head-grooves and the endwise movement of the swivel-shank in the swivel-bearing of the sash-plate, and the additional movement in the axial aperture of the strip-plate necessary to accommodate this separation is permitted by the 55 further movement of the swivel-pin in the guide-slots to the position shown by broken lines in Fig. 2. When the swivel-head is thus separated from the sash-plate hub, the hub- 60 ribs ride on the adjoining faces 29 of the head between the grooves until the ribs register with the next grooves, whereupon the action of the spiral spring acts to draw the head against the hub and the ribs into the grooves, 65 thus stopping the sash against further rota-

tion until the ribs are again forced out of the grooves, as before described, and in the same manner the sash can be rotated and stopped at various points.

When the sash and strips are alined, their 70 edge grooves and ridges, as well as the ribs and grooves on the sash-plate hub and swivel-head, act to stop the sash against rotation; but when the sash is turned out of line with the strips the latter ribs and grooves act alone to this 75 effect, and in this latter action the swivel has an endwise movement independent of and in addition to the endwise movement caused by the separation of the strips from the sash. While 80 the sash is described as bearing both on the swivel and on the pivot-hub, either one or the other of these bearings can be used as a principal bearing; but it is preferred to make the main bearing on the pivot-hub, because of the greater freedom thus given to the swivel for 85 its endwise movements.

What I claim as my invention, and desire to secure by Letters Patent, is—

1. In combination, a window-sash and a separable strip on its side edge, there being corresponding grooves and ridges on the adjoining faces, and a pivotal connection between the sash and the strip comprising a pivot-hub with an axial aperture on the one, a non-rotatable endwise-movable swivel in the aperture 90 having a head with grooves across its inner face, a bearing in the other adapted to operate on the pivot-hub having ribs with inclined sides on its end adapted to enter the head-grooves, and a spring acting to move the 100 swivel-head toward the pivot-hub.

2. In combination, a window-sash and a separable strip on its side edge, there being corresponding grooves and ridges on the adjoining faces, and a pivotal connection between 105 the sash and the strip comprising an axial aperture in the one, a non-rotatable endwise-movable swivel in the aperture having a head with grooves across its inner face, a rotatable bearing in the other between the one and the 110 swivel-head having ribs with inclined sides on its end adapted to enter the head-grooves, and a spring acting to move the swivel-head toward the one.

3. A pivotal connection for a window-sash 115 and a separable strip comprising a pivot-hub with an axial aperture on the one, a non-rotatable endwise-movable swivel in the aperture having a head with grooves across its inner face, a bearing in the other adapted to operate 120 on the pivot-hub having ribs with inclined sides on its end adapted to enter the head-grooves, and a spring acting to move the swivel-head toward the pivot-hub.

4. A pivotal connection for a window-sash 125 and a separable strip comprising an axial aperture in the one, a non-rotatable endwise-movable swivel in the aperture having a head with grooves across its inner face, a rotatable bearing in the other between the one and the 130

swivel-head having ribs with inclined sides on its end adapted to enter the head-grooves, and a spring acting to move the swivel-head toward the one.

5 5. A pivotal connection for a window-sash and a separable strip comprising an axial aperture in the one, a non-rotatable endwise-movable swivel in the aperture having a head on its outer end, a rotatable bearing in the 10 other between the one and the swivel-head, a spring adapted to move the swivel-head toward

the one, and means operated by the endwise movement of the swivel for retarding the rotation of the bearing.

In testimony whereof I have signed my ¹⁵ name to this specification in the presence of two subscribing witnesses.
